UNITED STATES PATENT OFFICE.

IRA D. SHAY, OF BALTIMORE, MARYLAND.

SCREW-DRIVER.

1,239,131.

Specification of Letters Patent. Patented Sept. 4, 1917.

Application filed July 25, 1916. Serial No. 111,259.

To all whom it may concern:

Be it known that I, IRA D. SHAY, a citizen of the United States, residing at Baltimore city, in the State of Maryland, have 5 invented a certain new and useful Improvement in Screw-Drivers, of which the following is a full, clear, and exact description.

The object of this invention is to provide a screw-driver having a plurality of points 10 or blades arranged longitudinally and transversely of the shank, so that screws so located that they are inaccessible to any one or more of the points or blades may be reached by one or more of the others of 15 them and be driven or drawn readily; and a further object of the invention is to provide a screw-driver that may be used to act upon screws used in those restricted places where ordinarily only bolts are commonly 20 used.

The invention consists of a screw-driver having a point or blade arranged in line with its longitudinal axis, and laterally extending points or blades arranged near the 25 first-named point or blade and so disposed as to be capable of use successively for turning a screw while operating in an arc of not over forty-five degrees, these last-mentioned points or blades being herein referred 30 to as "lateral blades" and the first-mentioned point or blade as the "longitudinal blade" for convenience; the lateral blades being disposed circumferentially around the shank, one in the direction of its length, another 35 transversely thereto, and the others alternating between the first two and lying in inclined planes and opposite one another so that one blade moved to its limit will leave the screw nick in position to be engaged by 40 the next succeeding blade when the screw-driver is moved into the starting position of its arc of movement from which it was last previously moved, as I will proceed now to explain and finally claim.

45 In the accompanying drawings illustrating the invention, in the several figures of which like parts are similarly designated, Figure 1 is an elevation with the intermediate portion of the shank broken out. 50 Fig. 2 is an elevation of the point or blade end of the screw-driver, looking down on Fig. 1. Fig. 3 is an end elevation, looking toward the right, Fig. 2. Fig. 4 represents a screw located in a place inaccessible to the 55 end blade of the screw-driver but accessible by means of one of the lateral blades, said

figure showing the screw-driver in dotted lines, and Fig. 5 represents an eighth turn that may be made within the restricted limit. Fig. 6 illustrates the screw-driver 60 having another one of its blades applied to the screw in the position at which it was left in Fig. 5 and capable of being advanced another eighth turn as shown in Fig. 7. Fig. 8 represents the screw as left in Fig. 7 65 and with another blade of the screw-driver applied to it so that it may be further advanced an eighth turn to the position shown in Fig. 9. Fig. 10 represents the screw as left in Fig. 9 and having still another blade 70 of the screw-driver applied to it whereby the screw may be given another eighth turn as indicated in Fig. 11. Fig. 12 is a side elevation illustrating the facility with which my improved screw-driver may be used in 75 connection with countersunk screws.

The shank 1 may be made or supplied with a handle 2 or formed at the handle-end in any suitable way. Its point end terminates in a point or blade 3 arranged in 80 line with the longitudinal axis of the screw-driver and adapted to engage a screw in any ordinary way. Arranged around the point of the shank at or near the point or blade 3 and extending laterally from the shank 85 are the blades 4, 5, 6 and 7, the blade 4 being arranged at right angles to the width of the blade 3 and running in the direction of the longitudinal axis of the screw-driver; the blade 5 being arranged obliquely to the 90 shank; the blade 6 being arranged transversely of the shank and at right angles to the blade 4; and the blade 7 likewise being arranged obliquely to the axis of the shank. These blades 4, 5, 6 and 7 are capable of 95 use when the screw-driver is presented horizontally or substantially so, and they are so arranged on the shank and disposed with relation to one another and the shank, that the screw-driver may be used to drive and 100 to draw screws located in otherwise inaccessible places or places accessible only with difficulty. For example, as illustrated in Figs. 4 to 11, suppose a screw be so placed that it is absolutely inaccessible to the blade 105 3 and is only accessible to one or more of the lateral blades, and furthermore, that a movement of the screw is only possible between the point 8, Fig. 4, and the point 9, Fig. 5. Should the nick in the screw be arranged as in Fig. 4, then it may be engaged by 110 the straight blade 4 and the screw-driver

then turned from the point 8 to the point 9, as shown in Fig. 5, whereby the screw will be given a turn through an arc of forty-five degrees, then the screw-driver will be turned 5 over and the screw thus last positioned engaged by blade 5 with the shank parallel to the obstruction 8, as in Fig. 6, and then when moved as before until arrested by the obstruction 9, the screw will be given another 10 eighth turn, as shown in Fig. 7, and then the screw-driver will be disengaged and turned over and its transverse blade 6 engaged with the screw under the same conditions, as in Fig. 8, and turned again to give 15 the screw another advance of forty-five degrees, as shown in Fig. 9, and then the screw-driver will be disengaged from the screw and turned over so that the screw will be engaged by the blade 7, as shown in 20 Fig. 10, and then the screw-driver again moved from 8 to 9 so as to complete the half revolution of the screw, as shown in Fig. 11; and these movements may be repeated until the proper adjustment of the screw is obtained. 25

As shown in Fig. 12, countersunk screws may be conveniently engaged by the lateral blades.

Illustrations 4 to 12 show how available 30 the screw-driver is for reaching difficult or ordinarily inaccessible places, and therefore it is possible to use screws in such places where heretofore bolts only have been capable of use.

I am aware that prior to my invention, 35 screw-drivers have been made with a number of points or blades disposed in various relations both longitudinally and transversely, and hence do not herein claim the broad idea of a screw-driver thus constructed, but I am not aware of a prior instance of a screw-driver containing at one 40 and the same end a series of blades so disposed with relation to the longitudinal axis of the screw-driver and to one another that 45 these blades may be used to operate screws

not only in accessible but in otherwise inaccessible places, as herein shown and described.

What I claim is:—

1. A screw-driver, having its shank provided with laterally projecting screw-engaging blades, one of them extending longitudinally, the next adjacent obliquely, the next adjacent transversely and the next adjacent obliquely, with relation to the shank, and succeeding one another circumferentially around the shank, whereby when turned around one by one they will be in position for successive engagement with the screw as it was left by the limit of action of the last preceding blade. 50 55 60

2. A screw-driver, comprising a shank having a series of laterally extended blades arranged circumferentially around the shank, one of the said blades running lengthwise of the shank, the opposite blade crosswise thereof, and the alternate blades obliquely thereto, whereby when the shank is arranged at right angles to the axis of a screw to be turned the said several blades may be successively used one after another to turn the screw one-half turn within a forty-five degree arc of movement of the screw-driver. 65 70 75

3. As an improved article of manufacture, a screw-driver having a blade arranged in line with its axis, and a series of lateral blades arranged circumferentially around the shank adjacent to its longitudinal blade, 80 one of these lateral blades being arranged lengthwise of the shank, another obliquely thereon, another transversely thereof and another obliquely thereto, said lateral blades adapted for successive use in the order 85 named to progressively turn a screw.

In testimony whereof I have hereunto set my hand this 21st day of July, A. D. 1916.
IRA D. SHAY.
